UNITED STATES PATENT OFFICE.

FREDERICK H. WALKER, OF PHILADELPHIA, PENNSYLVANIA.

DESIGN FOR AN EMBOSSED FABRIC.

47,059.

Specification for Design.

Patented Mar. 2, 1915.

Application filed November 12, 1914. Serial No. 871,797. Term of patent 3½ years.

To all whom it may concern:

Be it known that I, FREDERICK H. WALKER, a citizen of the United States, residing at Philadelphia, in the county of Philadelphia and State of Pennsylvania, have invented a new, original, and ornamental Design for Embossed Fabrics, of which the following is a specification, reference being had to the accompanying drawing, forming a part thereof.

Figure 1 is a plan view of an embossed

fabric illustrating my new design, and Fig. 2 is a view in section on the line 2—2 of Fig. 1.

I claim:

The original design for an embossed fabric, as shown.

FREDERICK H. WALKER.
